MACHINE FOR MAKING TUBS AND THE LIKE

Axel M. Walstrom, Minneapolis, Minn., assignor
to The Creamery Package Mfg. Company, Chi-
cago, Ill., a corporation of Illinois

Application September 29, 1938, Serial No. 232,294

9 Claims. (Cl. 147—1)

The invention relates to machinery for the manufacture of tubs and like containers of wooden stave construction, and more particularly to a machine for automatically producing successive sets of staves of precisely similar aggregate width for assembly into tubs or similar containers of accurate standard dimensions.

In the cooping of butter tubs and similar containers it is common practice to place a number of tapered wooden staves edge to edge on a curved "laying-out board" having fixed stops at each end which are spaced apart a distance equal to the exact total width of staves required to make a tub of the desired standard size. However, as the staves are of varying widths it is difficult to fit together a number of staves that will exactly equal the space between the end stops on the laying-out board, and the operator therefore spends considerable time trying various combinations of staves selected from a convenient supply of miscellaneous widths before a suitable set of staves is found to approximately fill the space on the board.

This practice is obviously slow and results in stave sets of slightly varying total width which in turn serve to make tubs of slightly different diameters on which hoops of fixed diameters are either too tight or too loose, it being the common practice to machine drive all hoops to predetermined positions on the tubs.

It is the principal object of my invention to provide automatic mechanical means for "laying out" sets of staves of exact and unvarying total width to assure their assembly into tubs of uniform size and tightness.

Another object is to provide automatic mechanism for continuously measuring a passing series of abutting staves and cutting the last stave in the series to the exact width necessary to produce a set of predetermined standard aggregate width for assembly into a tub.

A further object is to provide automatic mechanism for separating and moving apart from the others a series of staves which have been measured and cut to the desired aggregate width and comprising the requisite quantity for the assembly of a tub.

Other objects and advantages will be apparent in the following detailed description of a preferred embodiment of the invention which I have selected for illustration in the accompanying drawings. It will be understood, however, that various changes in form, construction and arrangement may be made by those skilled in the art without departing from the spirit and scope

of the invention as expressed in the appended claims.

Referring to the drawings, Fig. 1 represents a plan view of the machine comprising the mechanisms for measuring and cutting off the sets of staves. Fig. 2 is a front view in elevation of the mechanisms represented in Fig. 1. Fig. 3 is a cross-sectional view in elevation taken on the planes of the line 3—3 in Fig. 1. Fig. 4 is a cross-sectional view in part taken on the planes of line 4—4 in Fig. 3. Fig. 5 is a cross-sectional view in part taken on the planes of the line 4—4 in Fig. 3 and showing in addition the mechanism provided for engaging the last stave of a complete set and moving them along a table apart from the following series of staves. Fig. 5 is represented also by the line 5—5 in Fig. 6. Fig. 6 is a side elevation view of the essential parts of the stave set separating mechanism in their operating connection with associated parts of the other mechanisms.

Generally stated, the operative arrangement of the machine as herein illustrated comprises a supply table upon which has been piled a supply of previously jointed staves of miscellaneous widths, and a laying-out board upon which an operator places a series of the pre-jointed staves in lateral abutting relation preparatory to their being moved into the measuring and cutting mechanism. The latter-mentioned movement of the staves is accomplished by a conveyor operating longitudinally of the laying-out board and which engages the staves arranged on the board and moves them forward into engagement with a revolving drum, the drum having circumferential stave bearing portions of the exact diameters of the similarly located inside diameters of a finished tub.

As the staves pass over upon the revolving drum they are engaged on their upper surfaces by a pair of retaining wheels which bear upon the staves and hold them in firm position on the drum. The drum and the retaining wheels are provided with slots which are positioned in registry once in each complete revolution of the drum, and through which a slitting saw is operated to cut through the last stave of the number required to complete a set, the drum and wheels being stopped from rotation during the operation of the saw. Thereafter a pair of hook members are lowered into engagement with the last stave completing the set and the latter is moved forward on a receiving table pushing the other staves of the set ahead of it and permitting an attendant to gather together the staves of the complete set preliminary to further operations in the assem-

bly of the tub. The drum is then again put in operation with the staves being fed thereover for the measurement and cutting off of another complete set.

5 More specifically described with reference to the drawings the numeral 10 indicates a horizontally disposed laying-out board adapted to accommodate a series of tapered pre-jointed staves 11 lying in lateral abutment between an upwardly turned flange 12 at the curved rear edge of the board and another upwardly turned flange 13 at the curved front edge of the board.

10 A shelf 14 is provided rearwardly of the board 10 for the purpose of holding a supply of loose staves. Preferably also an extension shelf 15 is provided at the outer end of the laying-out board 10, which serves also to hold a supply of loose staves convenient for moving the staves forward to the laying-out board. The shelf 15 preferably is slightly above the laying-out board, so that the end edge of the shelf 15 serves as a limit gauge for a complete set of staves placed on the laying-out board.

15 The outer end of the laying-out board 10 is supported upon a standard 16 which also is provided with an extended bracket 17 which supports the rear shelf 14.

20 One end of the extension shelf 15 may be supported upon the adjacent end of the laying-out board, while the other end of the shelf may be supported by any conventional leg structure (not shown). The inner ends of the laying-out board 10 and rear shelf 14 are supported upon a cross bar 18 secured to the upper portions of a pair of upright frame members 19 and 20.

25 Positioned adjacent the end of the laying-out board 10 is a rotary drum 21 of conical outer contour and having its upper portion at a level slightly above the plane of the laying-out board. The drum 21 is constructed with its smaller end closed and provided with a hub portion 22 having free bearing on a stationary shaft 23 fixed at its respective ends in the frame members 19 and 20.

30 The open larger end of the drum is supported upon a pair of idler rollers 24 and 25 freely mounted on a pair of stationary shafts 26 and 27 which function also as cross-connecting bars between the frame members 19 and 20.

35 The drum is provided on its outer periphery with a pair of circumferential ribs 28 and 29, the diameters of which are the same as the internal diameters at similar locations in a tub of predetermined size to be assembled from the staves being laid out on the machine herein described.

40 The closed inner end of the drum 21 is provided with gear teeth 30 which are engaged by a driving pinion 31 fixed upon a short shaft 32 having suitable bearing in the frame member 19 and provided at its outer end with a pulley 33 driven by a belt 34, the latter extending to a pulley 35 freely rotating on a shaft 36 having its bearings in the frame members 19 and 20. The pulley 35 is driven by clutch means hereinafter described. The drum 21 is provided with a longitudinal slot 37 extending from a point adjacent to the closed smaller end of the drum to and through the larger outer end of the drum.

45 Mounted above the drum 21 is a pair of wheels 38 and 39 positioned oppositely over the circumferential ribs 28 and 29 formed on the drum. The wheels 38 and 39 are secured upon a shaft 40 having bearing support at its ends in a U shaped bracket 41 which is pivotally supported upon a

50 inwardly extended portions of the frame members 19 and 20.

The outer ends of the bracket 41 carry coiled springs 43 and 44 which latter are respectively attached to the frame members 19 and 20 and normally tend to draw downward the bracket 41 and cause the wheels 38 and 39 to bear upon the drum ribs with resilient tension.

55 The shaft 40 also carries a gear 45 secured thereto and in driven mesh with the gear teeth 30 provided on the smaller end of the drum 21. The wheels 38 and 39 and the gear 45 are formed with such diameters as will cause them to make two complete revolutions to one revolution of the drum 21. The wheels 38 and 39 are also provided with slots 46 and 47 across their peripheral portions so positioned as to be in registry with the slot 37 provided in the drum as the latter reaches topmost position in the revolution of the drum.

60 The slot 37 in the rotary drum and the slots 46 and 47 in the wheels when in registry provide passageway for the blade portion of a circular saw 48 mounted on a carriage 49 slidably supported on a pair of rails 50 and 51 outwardly secured upon the frame member 20 and inwardly secured upon a bracket collar 52 secured to the stationary shaft 23. The rails 50 and 51 are positioned in parallel relation to the topside of the drum 21.

65 The peripheries of the circumferential ribs 28 and 29 of the drum 21 operate adjacent to the end of the laying-out board 10, and by means of belt conveyors, hereinafter described, the staves are moved along the laying-out board and into engagement with the revolving drum. The staves being in close lateral abutment move forward upon the ribs 28 and 29 and pass under the retaining wheels 38 and 39, being so held in close engagement to the drum. The latter is operated, by means hereinafter described, to make one complete revolution and stop with the slot 37 in uppermost position in registry with the slots 46 and 47 in the retaining wheels. Thereupon, the saw 48 is passed longitudinally through the slots and cuts the stave lying between the drum and wheels, whereby the staves passed over the surfaces of the drum ribs in the one complete revolution of the drum are accurately measured to form a set of staves of the exact aggregate width necessary to preserve the standard diameter in the tub to be assembled therefrom.

70 The movement of the staves along the laying-out board, and into engagement with the rotary drum and the retaining wheels, is accomplished by means of a pair of belt conveyors 53 and 54 of which the upper runs lie on the upper surface of the laying-out board 10 and move longitudinally thereof, toward the drum with the staves lying on the belts, the belt operation occurring simultaneously with the rotation of the drum.

75 The belts 53 and 54 are supported adjacent the drum on a pair of idler pulleys 55 and 56 mounted beneath openings in the laying-out board 10 and supported on brackets 57 secured to the under-support 18 for the laying-out board. At the outer ends of their runs the belts 53 and 54 are supported upon drive pulleys 58 and 59 carried by a shaft 60 having suitable bearings in brackets 61 and 62 and mounted on the outer supporting standard 16 for the laying-out board. The pulley 59 is slightly larger in diameter than the pulley 58 in order to give slightly more speed to the belt 54 which underlies the wider portions of the tapered staves, and thereby retains the staves in

lateral abutment throughout their movement around the curved laying-out board 10.

The pulleys 58 and 59 and shaft 60 are driven by a sprocket 63 secured to the shaft and carrying a chain belt 64 extending to a drive sprocket 65 secured on a shaft 66 having suitable bearings provided in a bracket 67 mounted on the cross connecting bar 26 and in the frame member 19. The shaft 66 is provided with a beveled gear 68 in driven mesh with another beveled gear 69 secured to a spur gear 70 which latter is in driven mesh with the gear teeth 30 formed on closed end of the drum 21. The beveled gear 69 and spur gear 70 are freely rotatable as a unit on the cross bar or shaft 26 connecting the frame members 19 and 20.

Further describing the operating means for the sawing mechanism, the carriage 49 on which the circular saw 48 is supported is controlled in its movements by a unitary pair of connecting rods 71 attached to the carriage and extending rearwardly, the rear ends being integral with a cross member 72 having pivotal support in a pair of spaced bearing blocks 73 and 74 carrying a pulley shaft 75. Each of the blocks 73 and 74 is rigidly secured to the upper ends of one of two pairs of swinging bars 76 and 77, which latter are rigidly secured at their lower ends in a similar pair of bearing blocks 78 freely supported on a drive shaft 79. Shaft 79 is operatively mounted to suitable bearings provided on the extended ends of the cross members 80 and 81 fixed in the frame members 19 and 20. It will be observed that in the plan view shown in Fig. 1 the swinging bars 76 and 77 are represented to be in intermediate vertical position, while in Fig. 3 the bars as represented by the one pair 77 are shown to be in rearmost inclined position.

The shaft 79 has secured thereon a pulley 82 carrying a belt 83 in driving engagement with another pulley 84 secured to the shaft 75. Secured to the latter shaft also is a double groove pulley 85 supporting a pair of V belts 86 running to a pair of single groove pulleys 87 mounted on the saw shaft 88 operatively supported on the carriage 49, the pulleys 87 being positioned on opposite sides of the saw 48. The shaft 79 is provided with a driving pulley 89 for driven connection by belt or otherwise with a source of power (not shown).

The shaft 79 also is in driving connection with a conventional worm and gear drive mechanism 90, the shaft 79 carrying the worm in that unit of which the driven gear is secured to the extended rear end of the shaft 36. Mounted on the shaft 36 adjacent to the frame member 20 is a free running pulley 91 adapted for clutch drive as hereinafter described, and connected by a belt 92 with a pulley 93 mounted on the worm shaft 94 in another conventional worm and drive transmission unit 95, and there-through having driving connection with the gear shaft 96 of that unit, the latter shaft having suitable bearing support in the side portions of the frame member 20.

The shaft 96 has secured on its respective ends outwardly of the frame member 20 a pair of discs 97 and 98 which carry respectively crank pins 99 and 100. Pivottally connected to the crank pins 100 are a pair of connecting rods 101 and 102 each of which has opposite pivotal connection with a cross member 103 suitably secured to the mid-portions of the respective pairs of swinging bars 76 and 77.

Rotation of the discs 97 and 98 causes the

swinging inwardly of the bars 76 and 77, which in turn causes the saw carriage to move the circular saw 48 through the slots 37, 46 and 47, and to return the saw to outward position after cutting the stave positioned between the slots, as previously described.

The operation of the discs 97 and 98 is controlled by clutch means comprising a clutch collar 104 splined upon the shaft 36 and engageable with the mating clutch member provided on the adjacent side of the free running pulley 91. Operation of the splined clutch collar 104 is controlled by a yoke 105 having pivotal support at its upper end upon a fixed bar 106 supported in the frame members 19 and 20, and provided intermediately with a pair of pins 107 engageable in a slot conventionally provided in the clutch member 104.

Movement of the yoke 105 is controlled by a shifting bar 108 having pivotal connection at 20 one end with the lower swinging end of the yoke 105. The bar 108 extends forwardly and is pivotally connected at its opposite end with another yoke member 109 having intermediate pivotal support at 25 110 on the stationary bar 106.

Intermediately of the supporting bar 106 and the shifting bar 108, the yoke 109 is provided with a pair of pins 111 engaged in the conventional slot provided in a clutch member 112 splined on the front end of the shaft 36 and engageable with a complementary clutch member provided on the adjacent side of the free running pulley 35 previously described as part of the driving means for the rotation of the drum 21.

The yoke 109 extends upwardly of its pivotal support on the bar 106 and is pivotally connected at its upper end with a reciprocating latch pin 113 having sliding bearing support in the frame member 19. The latch pin 113 is adapted to be moved into and out of engagement with a pin hole 114 provided in the end portion 22 of the drum 21. The pin hole 114 is so positioned that when the pin 113 is in engagement therewith the slot 37 for the passage of the saw is in uppermost position in the rotation of the drum.

Movement of the shifting bar 108 is controlled alternatively to disengage the pin 113 from the rotary drum and cause the latter by engagement of the clutch member 112 with pulley 35 to rotate one full revolution, thereupon re-engaging pin 50 113 with the drum to secure it in position with the slot in registry with the path of the circular saw, and at the same time to engage the other clutch member 104 with pulley 91 to cause the saw to travel inwardly through the slot 37 to 55 sever the stave positioned thereover and return to outward position, whereupon both clutch members are disengaged and the mechanisms brought to a complete stop.

This cycle of operation is initiated by means of a foot pedal 115 mounted on a shaft 116 having suitable bearings in floor brackets 117 and also carrying a lever 118 having pivotal engagement with another lever 119 secured to a rock shaft 120 having suitable bearing support 65 in floor brackets 121.

Secured to the rock shaft 120 is a pair of levers 122 extending upward alongside the shifting bar 108 and adjacent to a pin 123 fixed in the shifting bar. A coil spring 124 secured at one end 70 to the frame member 19 and at its other end to the shifting bar 108, normally tends to shift the bar forwardly or to the right as appearing in Fig. 3. Another coil spring 125 is attached at one end to a cross bar 126 fixed upon the 75

frame bars 80 and 81, and at the other end to the upright lever 122, the spring normally tending to retract the lever 122 away from the pin 123. Upon depression of the pedal 115, the upright lever 122 is moved into contact with the pin 123 and the shifting bar 108 is moved to cause withdrawal of the latch pin 113 from the closed end or head of the drum 21, and at the same time to engage the clutch member 112 and pulley 35, whereupon the drum 21 is rotated one complete revolution as previously described.

Upon the start of the revolution of the drum 21, while the pedal 115 is depressed, the pin 113 is held withdrawn from the opening 114 in the drum. Upon release of the pedal, the pin 113 contacts the end portion of the drum 21, under tension of the spring 124 applied through the shifting bar 108 and yoke 109, in position to re-enter the pin hole 114 in the end of the drum and stop the movement of the latter upon completion of one revolution. Upon re-engagement of the pin 113 in the pin hole provided in the head of the drum, the shifting bar 108 is permitted to move to the extreme frontward position under tension of the spring 124 and causes engagement of the other clutch member 104 and pulley 91, thereupon starting the revolution of the saw carriage controlling discs 97 and 98. These discs rotate for one complete revolution accomplishing the entry of the saw into and through the slot provided in the drum and return to outward position.

Upon completion of one revolution of the discs 97 and 98, a peripheral notch 127 provided in each of the discs is simultaneously engaged by one of a pair of upright bars 128 and 129, each of the latter having a bent end portion normally in engagement with the periphery of one of the discs. The upright bars 128 and 129 extend downwardly in pivotal engagement respectively with a pair of levers 130 and 131 secured to the opposite end portions of the rock shaft 120 at substantially right angles to the shifting bar pin engaging levers 122.

Upon engagement of the notches 127 with the upper ends of the bars 128 and 129 the latter are forced downward and thereby cause the levers 122 to engage the pin 123 on the shifting bar 108 and move the latter reversely against the tension of spring 124 to disengage the clutch member 104 from pulley 91, and stop the rotation of the discs 97 and 98. The upright bars 128 and 129 remain in engagement in the notches 127 and thereby hold the shifting lever 108 in the position in which both clutch members are disengaged and the operation of both the saw carriage and the revolving drum is stopped. It will be observed however, that the main drive shaft 79 is continued in operation, and the drive to the circular saw is continued to maintain the latter at cutting speed.

Upon depression again of the pedal 115, the upright bars 128 and 129 are drawn further downward, and by that movement are thrown out of engagement with the notches 127 in the discs and clear of the periphery of the latter by means of the links 132 and 133, each pivotally connected at one end to one of the bars 128 and 129 and at the other end to the frame member 20, the links 70 being in such relative angular position as to move the bars outwardly from the peripheries of the discs with the downward movement of the bars.

Upon completion of the revolution of the drum 75 and the automatic reverse shifting of the shifting

bar 108, the upright bars 128 and 129 are suddenly lifted, and by reason of the longitudinally slotted connections between the bars and the links, indicated at 134, the bars pass to the outer ends of the slots 134 provided in the link, and move outwardly and above the notches 127 in the discs, thus not preventing the start of the rotation of the discs 97 and 98. Upon coming to rest, the upper hooked ends of the upright bars ride upon the periphery of the discs above the notches 127 in position to be re-engaged by the notches upon the completion of one revolution of the discs.

Upon re-engagement of the disc notches with the ends of the bars 128 and 129, the shifting bar 108 is moved to neutral position as hereinbefore described, and the cycle of the measuring and sawing operations is completed and the driving mechanisms therefor brought to a stop.

The measured and sawed set of staves for one complete tub is moved off from the drum 21 and 20 onto a receiving table 135 supported on a standard 136 and positioned oppositely from the laying-out board 10. This may be accomplished automatically by means of the mechanism shown in Figures 5 and 6, and which may be incorporated with the other mechanisms hereinbefore described in the complete machine or omitted as may be desired or convenient in the installation of the machine. Representation of the drum 21 has been omitted from Fig. 6, for clarity of illustration.

The stave withdrawing mechanism disclosed comprises a pair of hooks 137 having their free pointed ends normally positioned above and at the delivery side of the slot 37 in the rotating 35 drum. The hooks 137 are rigidly attached to a U shaped bracket 138 having pivotal support at its respective ends upon a pair of levers 139 and 140 secured upon a shaft 141 having suitable bearing support in brackets provided on the supporting standard 136.

The swinging portion of the U shaped bracket 138 carrying the hooks rests at one side upon a curved shoe 142 having pivotal support at its outward end in a suitable bracket 143 provided 45 on the receiving table 135, and with its inner end pivotally supported by a pin 144 fixed in the upper end of a vertically slid able bar 145 having a slot 146 within which are positioned a pair of bolts 147 secured to the frame member 20 and 50 serving to retain and guide the reciprocating bar 145. The lower end of the bar 145 is provided with a roller 148 having engagement with a cam 149 provided on the hub of the disc 98. The lever 140 is provided with an angular extension 55 150 at the outer end of which is pivotally connected a link bar 151 extending downwardly in pivotal connection with a lever 152 having opposite pivotal support at 153 upon the frame member 20. The lever 140 is also provided with an 60 oppositely extending angular portion 154 to which is attached one end of a coil spring 155 oppositely attached to the U shaped bracket 138 and tending to retain the bracket in bearing contact upon the shoe 142.

Intermediately of the lower lever 152 is provided a bracket 156 to which is pivoted a link 157 having a slot 158 in its upper end engaging the crank pin 100 on the disc 98.

In operation, the mechanism just described remains in the position disclosed in Figures 5 and 6, during the travel of the saw 48 inwardly through the slot 37 in the rotary drum, and until the sawing operation on the stave overlying the slot has been completed. This sawing operation is com- 70 75 95

pleted during one-half revolution of the disc 98 in the direction indicated in Fig. 6, and during which the crank pin 100 has moved from the lower to the upper extremity of the slot 158 in the link bar 157 and has returned to the lower extremity of the slot. With the further rotation of the disc 98, and during the return movement of the saw 48 outwardly from the slot 31, the cam 149 permits the sliding bar 145 to drop to lowermost position, thereby lowering the curved shoe 142 and permitting the hooks 131 to drop into engagement with the severed portion of the stave on the delivery side of the slot 31 in the drum. At this time also, the crank pin 100 forces downward the connecting link 157 and operates through the lever 152 link 151 and lever 140 to move the hooks, now engaged with the last stave, outwardly and over the receiving table 135, thus propelling the series of staves along the latter table.

Upon completion of the full revolution of the disc 98, a spring 159 attached to the lever 152 at one end and to a suitable bracket provided on the table supporting standard 136 effects the return of the hooks 131 to normal position as shown in Fig. 5, and at the same time the cam 149 has lifted the sliding bar 145 and thereby the curved shoe 142 which effects the lifting of the hooks above and free of the path of the staves passing over the drum during the next cycle of operation.

I claim as my invention:

1. Apparatus for laterally measuring and cutting a set of staves for assembly into a container of predetermined size comprising in combination, a rotary device having peripheral contour equivalent to the inside lateral contour of said container, means for rotating said device in intermittent cycles of one revolution, means for passing a laterally abutting series of staves in successive contact with said device through a predetermined position in its peripheral path of rotation, means for maintaining said staves in contact with said device while passing through said position, stave severing means normally supported adjacent the path of movement of said staves and operable transversely of said path of movement, and means operable between the cycles of one revolution of said device to move said stave severing means across the path of movement of said staves at said predetermined position and to sever the stave then positioned therein.

2. Apparatus of the class described comprising in combination, a rotary drum operable to measure the aggregate width of a series of staves passing successively in contact with the periphery of said drum, said drum having a longitudinal slot extending through its peripheral wall, a pair of wheels operatively supported for outward bearing upon said staves in contact with said drum, said wheels having peripheral slots therein, driving means for said drum and said wheels causing the slots in said wheels to register with the slot in said drum once in each revolution of said drum, means for stopping said drum and said wheels with said slots positioned in register, a saw operatively supported for passage through said slots when so positioned in register to sever a stave held between said drum and said wheels, and means operable after the stoppage of said drum and wheels to move said saw through said slots.

3. Apparatus of the class described comprising in combination, a rotary drum operable to measure the aggregate width of a series of staves pass-

ing successively in contact with the periphery of said drum, said drum having a longitudinal slot extending through its peripheral wall, a pair of wheels operatively supported for outward bearing upon said staves in contact with said drum, said wheels having peripheral slots therein, driving means for said drum and said wheels causing the slots in said wheels to register with the slot in said drum once in each revolution of said drum, means for stopping said drum and said wheels with said slots positioned in register, a saw operatively supported for passage through said slots when so positioned in register to sever a stave held between said drum and said wheels, means operable after the stoppage of said drum and wheels to move said saw through said slots, and reciprocating means operable to engage the severed portion of said stave and remove said portion from said drum.

4. Apparatus of the class described comprising in combination, a rotary drum having a slot extending longitudinally through its peripheral wall, a pair of wheels operatively positioned adjacent the periphery of said drum and having peripheral slots therein, a movable support for said wheels, said support having resilient means tending to move said wheels toward said drum, driving means for said drum and said wheels adapted to cause the slots in said drum and said wheels to be in register after one revolution of said drum, releasable means for securing said drum and said wheels in position with said slots in register, a saw normally positioned outwardly of said slots when in register, operating and supporting means for said saw operable to move said saw longitudinally through said slots and back to normal position, clutch means controlling the operation of said drum and wheel driving means, clutch means controlling the operation of said saw moving means, and control means manually operable to release said securing means and to engage said drum driving control clutch and automatically operable serially thereafter, to re-engage said securing means after one revolution of said drum, to disengage said drum driving control clutch, to engage said saw moving control clutch, and to disengage said latter clutch after one cycle of movement of said saw through said slots and return.

5. Apparatus of the class described comprising in combination, a rotary drum adapted for peripheral contact with a series of passing staves, said drum having a longitudinal slot in its peripheral wall, means for securing said staves in contact with said drum at a predetermined position in the path of rotation of said drum, means for rotating said drum, a latch member operable to stop rotation of said drum and secure said drum against movement when said slot is in said predetermined position, a clutch controlling the operation of said drum rotating means, a lever having operative connection with said latch member and said clutch and operable alternately to release said latch member and effect driving engagement of said clutch and to cause disengagement of said clutch and re-engagement of said latch member with said drum after one revolution of said drum, cutting means operable through said slot to sever a stave secured in said predetermined position over said slot, and means operable after engagement of said latch member with said drum to move said cutting means through said slot.

6. Apparatus of the class described comprising in combination a rotatable drum having a longitudinal slot through its peripheral wall,

means operable to stop rotation of said drum with said slot in a predetermined position, a saw, a reciprocal support operable to move said saw through said slot, means for operating said reciprocal support, said means including a crank disc effective in one revolution thereof to cause the movement of said saw into and out of said slot, driving means for said crank disc, a clutch for controlling operation of said crank disc driving means, a lever having operative connection with said clutch and operable to effect engagement of said clutch and start rotation of said crank disc, a shifting bar attached to said lever, and means operatively connected to said shifting bar and engageable by said crank disc after one revolution to cause said shifting bar to disengage said clutch and stop rotation of said crank disc.

7. Apparatus of the class described comprising in combination, a rotatable drum having a longitudinal slot through its peripheral wall, means operable to stop rotation of said drum with said slot in a predetermined position, a saw normally positioned outwardly of said slot when in said predetermined position, means for moving said saw inwardly through said slot and outwardly to normal position, a crank disc for actuating said saw moving means and operable through one revolution during the inward and outward movement of said saw, said crank disc having a peripheral notch, driving means for said crank disc, a clutch for controlling operation of said driving means, a lever operable to effect engagement of said clutch to start operation of said driving means, a shifting bar attached to said lever, another lever engaged with said shifting bar, and a reciprocating bar pivotally connected to said latter lever and extending into position for engagement by said notch upon completion of one revolution of said crank disc whereby said latter lever, shifting bar and clutch lever may be actuated to disengage said clutch and stop operation of said saw moving means.

8. Apparatus of the class described comprising in combination, a rotatable drum adapted to support a series of staves passing in peripheral contact therewith and having a longitudinal slot in its peripheral wall, means operable to stop rotation of said drum with said slot in a predetermined position, a saw normally supported outwardly of said slot when in said predetermined position, means for moving said saw inwardly through said slot to sever a stave positioned thereover and outwardly to normal position, a

crank disc for actuating said saw moving means operable through one-half revolution during the inward movement of said saw and through the other half revolution during the outward movement of said saw, a stave engaging device normally positioned in spaced relation to said drum adjacent said slot, and means connected with said crank disc and operable during the latter half revolution thereof effective to move said device into engagement with a severed portion of 10 the stave positioned over said slot and move said stave portion laterally away from said drum.

9. Apparatus of the class described comprising in combination, a rotatable drum adapted to support a series of staves passing in peripheral contact therewith and having a longitudinal slot in its peripheral wall, means operable to stop rotation of said drum with said slot in a predetermined position, a saw normally supported outwardly of said slot when in said predetermined position, means for moving said saw inwardly through said slot to sever a stave positioned thereover and outwardly to normal position, a crank disc for actuating said saw moving means operable through one-half revolution during the 15 inward movement of said saw and through the other half revolution during the outward movement of said saw, a stave engaging device normally positioned in spaced relation to said drum adjacent said slot, a shoe normally supporting 20 said device in said spaced relation to said drum and operable to cause said device to engage a severed portion of the stave positioned over said slot, a cam mounted on said crank disc, a bar having pivotal connection with said shoe and having operative engagement with said cam, said cam and bar being effective to maintain said spaced relation between said device and said drum during the initial half revolution of said crank disc and to cause said device to engage 25 said severed stave portion during the latter half revolution of said crank disc, lever means pivotally connected to said device and operable to move said device and said engaged stave portion laterally away from said drum, a connecting bar 30 having pivotal attachment to said lever means, and a crank pin on said crank disc, said connecting bar and said crank pin being inter-engaged for free relative movement during the initial half revolution of said crank disc and to cause said connecting bar to operate said lever means during 35 the latter half revolution of said crank disc.
